UNITED STATES PATENT OFFICE.

AGOSTINO REA, OF HELPER, UTAH.

COAL-MINING MACHINE.

1,271,617.

Specification of Letters Patent.

Patented July 9, 1918.

Application filed February 14, 1918. Serial No. 217,134.

To all whom it may concern:

Be it known that I, AGOSTINO REA, a citizen of the United States, residing at Helper, in the county of Carbon and State 5 of Utah, have invented certain new and useful Improvements in Coal-Mining Machines; and I do declare the following to be a full, clear, and exact description of the invention, such as will enable others skilled 10 in the art to which it appertains to make and use the same.

My invention relates principally to that class of mining machines employing a vertically disposed supporting frame, a coal 15 drill, a feed nut through which the shaft of the drill is threaded, and driving means for the drill carrying shaft including gearing mounted on a horizontal frame which is adjustable vertically along said supporting 20 frame.

One object of my invention is to provide an attachment to be used in connection with the parts above set forth for the purpose of accurately controlling the speed at which the 25 drill is advanced to the work, and to this end a further object is to so construct the attachment as to permit its use without in any way altering the old parts of the machine.

30 A still further object of the invention is to provide an electric motor for driving the gearing of the drill operating means, and to so construct the horizontal frame above mentioned, as to permit mounting of the motor 35 on one end of this frame and positioning of the gearing at the other end thereof.

With the foregoing general objects in view, the invention resides in the novel features of construction and unique combination of 40 parts to be hereinafter fully described and claimed, the descriptive matter being supplemented by the accompanying drawings which form a part of this specification and in which:—

45 Figure 1 is a side elevation of a mining machine constructed in accordance with my invention, the upper end of the vertical supporting frame being broken away;

50 Fig. 2 is a horizontal section on the plane of the line 2—2 of Fig. 1, illustrating a top plan view of the drill carrying shaft, the feed nut, and the attachment which is interposed between this nut and the bearing of the gear which drives said shaft;

Figs. 3 and 4 are transverse sections on 55 the planes indicated by the lines 3—3 and 4—4 of Fig. 2;

Fig. 5 is a central longitudinal section through the feeding means of the drill carrying shaft, this view being cut substantially on the plane of the line 5—5 of Fig. 2;

Fig. 6 is a sectional view on the plane indicated by the line 6—6 of Fig. 2, showing a side elevation of the feeding means;

Figs. 7 and 8 are horizontal sections on the 65 planes of the lines 7—7 and 8—8 of Fig. 1, showing respectively a top and a bottom view of the motor supporting frame; and

Fig. 9 is a detail side elevation showing 70 a saw attachment applied.

In the drawings above briefly described, the numeral 1 designates a vertically disposed supporting frame having suitable adjustable prongs 2 at its upper and lower ends, the side bars of said frame having vertically spaced notches 3 in one edge, this exact construction being well known and therefore forming no individual part of my 75 invention.

The drill 4 is provided on its rear end 80 with a socket 5 receiving a tapered plug 6 on the front end of a drill carrying shaft 8 whose rear end is also provided with a tapered plug 9. The shaft 8 is threaded through a split nut 10 whose two halves are 85 secured together by the usual key 11 said nut being provided with the well known oppositely extending arms 12 which are usually received in the notches 3 of the bars of which the frame 1 is constructed. Due to 90 the nature of the present invention, however, the nut 10 is spaced from the frame 1 as will be hereinafter set forth. The rear end of the nut 10 is provided with the usual sectional socket 13 which was formerly positioned around the polysided head or plug 14 of the well known right angular bearing bracket 15 (see Fig. 5). In accordance 95 with my invention, however, the socket 13 engages a part of the attachment above referred to, and a socket on such attachment cooperates with the plug 14.

A beveled gear 16 is rotatably supported by the upper end of the bearing bracket 15 and is provided with keys 17 receivable in 105 longitudinal keyways 18 formed in opposite sides of the shaft 8, so that this shaft may slide through the gear but will at the same

time be rotated thereby. Gear 16 meshes with a pinion 19 on the upper end of a short vertical shaft 20 whose lower end is provided with a plug 21 receivable in the socket 5 22 at one end of a universal joint 23, this joint being carried by one end of a vertical drive shaft 24 which is driven by means yet to be described.

The attachment above referred to (featured in Figs. 2 to 6) is constructed as follows:

A brake drum 25 is provided on one end with a suitably shaped plug 26 for reception in the socket 13 of the usual split nut 10, the 15 opposite end of said drum having a central socket 27 into which one end 28 of a supporting member in the form of a split sleeve 29 projects, said drum being thus rotatably mounted on said supporting member. The 20 drum 25 is provided with a central bore 30 through which the shaft 8 passes and the split sleeve 29 surrounds said shaft as shown clearly in Fig. 5. The end of the supporting sleeve 29 opposite the journal 28 thereof, is 25 provided with a socket 31 adapted to receive the plug 14 of the bearing bracket 15 as is also clearly shown in Fig. 5. The supporting sleeve 29 occupies the space in which the split nut 10 was formerly located, and 30 said sleeve is provided with oppositely extending arms 32 which are receivable in the notches 3 for supporting the shaft 8 and adjacent parts in any required position.

A brake band 33 surrounds the brake drum 35 25 and is held against removal therefrom in one direction by an annular flange 34 with which said drum is provided. An adjusting screw 35 having a hand wheel 36, is provided for operating the brake band 33 so as 40 to either permit the brake drum 25 to rotate or to hold this drum against rotation. By this means, therefore, the split nut 10 may be permitted to rotate with the shaft 8 or may be held against rotation with said 45 shaft, and thus this shaft may be fed forwardly as required.

The screw 35 is swiveled in one end of an angular bracket arm 37 which is removably secured by means of a key 38 to a lug 39 extending from one half of the split sleeve 29. On the other half of this sleeve is secured a lug 40 through which a set screw 41 is threaded, said set screw bearing against the lower end of the arm 37 to hold the two 55 halves of the sleeve 29 together. The arm 37 rests at its lower end upon a flat surface 37' so that tightening of the screw 41 cannot tilt said arm. Arm 37 not only provides means for mounting the screw 35, but it will 60 be obvious from the drawings that this arm prevents removal of the journal 28 from the brake drum 25, unless key 38 is removed. When this is done, however, the two parts may be separated. This separation is necessary 65 when the bearing bracket 15 and its

coacting parts must be removed to permit the machine to be operated directly from the end of the shaft 8.

From the foregoing, taken in connection with the accompanying illustration, it will be obvious that the attachment is of simple and inexpensive nature, and that it may be easily applied. In installing this device, the key 11 of nut 10 is removed to permit expanding of this nut, so that its socket 13 70 may be disengaged from the plug 14. The socket 31 of the supporting sleeve 29 is now engaged with plug 14 by first expanding the sleeve by loosening the set screw 41 and removing the key 38. This having been done, 75 the brake drum 25 is rotatably engaged with the journal 28 by positioning the latter in the socket 27, and the sleeve in question may then be again connected with the brake band 33 by re-insertion of key 38, and the screw 80 41 tightened to clamp the two halves of the sleeve tightly together. The arms 32 of the sleeve 29 are received in the notches 3 previously occupied by the arms 12 of the nut 10, and this nut is secured to the drum 85 25 by closing its socket 13 around the plug 26 of said drum, after which the key 11 is driven in place. When installed as set forth, the attachment may be used as follows:

When drilling in soft coal, the brake band 33 may be tightly clamped around the drum 25 by proper actuation of the hand wheel 36, and when the parts are thus arranged, rotation of the shaft 8 will not only drive 100 the drill 4, but will cause this shaft to travel through the nut. In drilling in hard coal, the brake drum 25 at the start is permitted to rotate with the nut 10, by proper release of the brake 33. The drill will thus 105 rotate but will not feed ahead. By now gradually tightening the screw 35, the nut 10 will be slowly brought to a standstill so that the feeding of the drill will begin 110 gradually. If necessary, the brake band 33 need not be entirely contracted around the drum 25 and thus the required slippage between these parts may take place to permit extremely slow feeding of the drill. In other words, this slippage will permit the 115 nut 10 to rotate to the required extent with the shaft 8, but the rotation of such nut will nevertheless be retarded sufficiently to cause it to feed the shaft 8 to the required extent. The attachment may be operated 120 the same way whether the machine is drilling horizontally or vertically.

The foregoing completes a detail description of one feature of the invention, the other feature residing in the horizontal 125 frame 45, the gearing 46 at one end of said frame for driving the shaft 24 and numerous attachments, and the motor 47 supported by the other end of the frame. Frame 45 as featured in Figs. 1, 7 and 8, 130

includes a pair of parallel side bars 48 and a rigid transverse bar 49, said side bars extending across the side bars of frame 1, whereas bar 49 abuts the rear edges of said bars to prevent tilting of the frame 45 around the keys 50 which secure this frame in place by passage into the notches 3.

As shown most clearly in Figs. 1 and 7, the motor 47 is positioned partly between the ends of the side bars 48 and is provided with a vertical lug 51 having an opening through which a transverse pin 52 is passed, said pin also extending through ears 53 which rise from said side bars. By this means, the motor is supported from the frame 45 in such a manner as to permit it to be easily detached whenever required. This form of attaching means for the motor also permits the latter to be of a well known construction, no alterations being necessary in adapting it to the new use. A suitable detachable connection 54 is provided between the motor 47 and the gearing 46 and all bearings of this gearing are preferably of the 25 roller or ball type, in order to reduce friction to the minimum.

Two short transverse shafts 55 and 56 are driven by the gearing 46, said shaft 55 being preferably equipped with an emery wheel or the like 57 by which the drill 4 may be sharpened whenever necessary. A hand crank such as 56' (Fig. 7) may be used upon the shaft 56 for driving the machine by hand when motor 47 is removed, but when this motor is in use, a saw attachment 58 may well be mounted on the shaft 56 as disclosed in Fig. 9, a suitable spring device 59 being preferably connected to the attachment 58 and passed around a suitable 35 guide 60 on frame 45, for the purpose of feeding the saw toward the work. Except when its use is necessary, the attachment 58 will remain detached from the machine, but whenever it is to be used, the attachment 45 may be quickly and easily applied.

From the foregoing, taken in connection with the accompanying drawings, it will be obvious that although my invention entails little departure from the mining machines now commonly employed, it will produce a device which is much more efficient and advantageous in every way. Particular emphasis is laid upon the novel feeding means for the drill carrying shaft and upon the provision of the frame 45, these being the principal improvements which I have made over the old machine. Since probably the best results are obtained from the several details shown and described, these details are preferably employed, but I wish it understood that within the scope of the invention as claimed, numerous minor changes may well be made.

I claim:

1. An attachment for mining machines

comprising a brake drum having on one end a plug for reception in the socket of the usual feed nut of the machine, a brake coacting with said drum, and means for supporting said brake from the frame of the 70 machine.

2. An attachment for mining machines comprising a brake drum and means for attaching it to the feed nut of a mining machine, a brake coacting with said drum, a 75 supporting member for said brake and drum, and means for supporting said supporting member from the usual frame of the machine.

3. An attachment for mining machines 80 comprising a brake drum and means for attaching it to the feed nut of a mining machine, a brake coacting with said drum, a supporting member for said brake and drum, and oppositely extending arms on said supporting member for supporting said member from the usual frame of the machine.

4. An attachment for mining machines comprising a brake drum and means for attaching it to the feed nut of a mining machine, a brake coacting with said drum, a 90 supporting member for said brake and drum, means for supporting said supporting member from the usual frame of the machine, and a socket on said supporting member to 95 receive the plug on the bearing of the usual drill shaft driving gear.

5. An attachment for mining machines comprising a brake drum and means for attaching it to the feed nut of the machine, a 100 support in the form of a split sleeve, a bearing connection between one end of said sleeve and said drum, a sectional socket on the other end of said sleeve for passage around the plug of the usual bearing of the 105 drill shaft driving gear, means for supporting said sleeve from the frame of the machine, and a brake coacting with said drum.

6. An attachment for mining machines comprising a brake drum and means for attaching one end of said drum to the usual feed nut of the machine, the other end of said drum having a central socket, a supporting member for said drum in the form of a split sleeve, one end of said sleeve extending into said socket and forming a journal for said drum, a sectional socket formed on the other end of said sleeve for passage around the plug of the usual bearing of the 115 drill shaft driving gear, and a brake co- 120 acting with said drum.

7. An attachment for mining machines comprising a brake drum, having on one end a plug for reception in the socket of the usual feed nut of the machine, a support 125 in the form of a split sleeve alined with said drum, a bearing connection between one end of said support and said drum, a sectional socket formed on the other end of said sleeve, for passage around the plug on 130

- 4
- the usual bearing on the drill shaft driving gear, means for supporting said sleeve from the frame of the machine, and a brake co-acting with said drum.
- 5 8. An attachment for mining machines comprising a brake drum and means for attaching one end thereof to the feed nut of the machine, the other end of said drum having a central socket, a supporting member having a journal received in said socket to rotatably support said drum, a bracket for supporting said brake band, said bracket being secured to said supporting member and means for supporting said supporting member from the frame of the machine.
- 10 9. A mining machine comprising a supporting frame including a pair of vertical side bars, a horizontal frame including a pair of horizontal side bars extending across
- 15
- said vertical bars, means for connecting the two frames, a drill, a motor for driving said drill, said motor being positioned between the side bars of said horizontal frame at one end of the latter, a lug on said motor having an opening, and a transverse pin 25 passing through said opening for supporting said motor from said horizontal bars in a detachable manner, and means for applying hand power for driving the drill when said motor is removed.
- 30
- In testimony whereof I have hereunto set my hand in the presence of two subscribing witnesses.
- AGOSTINO REA.
